UNITED STATES PATENT OFFICE.

SAMUEL ADRIAN HARRINGTON, OF RICHMOND, VIRGINIA.

TYPE-WRITER.

1,211,147.

Specification of Letters Patent.

Patented Jan. 2, 1917.

Application filed April 21, 1915. Serial No. 22,827.

To all whom it may concern:

Be it known that I, SAMUEL A. HARRINGTON, a citizen of the United States, residing at Richmond, in the county of Henrico and 5 State of Virginia, have invented certain new and useful Improvements in Type-Writers; and I hereby declare that the following is a full, clear, and exact description thereof, reference being had to the accompanying 10 drawings, which form part of this specification.

This invention relates to typewriting machines in which the paper is carried on a printing roller mounted in a carriage which 15 moves across the machine during the operation of printing a line and at the end of the operation the roller is given a turn sufficient to space for a new line while the carriage is returned to its initial starting 20 position.

In typewriting machines as ordinarily constructed the printing roller is turned the space of a line or several spaces, as desired, by means of a lever pivoted on the carriage 25 and having one arm arranged within easy reach of the operator and the other arm engaged with a ratchet on the printing roller so that when the lever is tilted by the hand of the operator the paper roller will be 30 turned sufficiently to space for the next line and release the feed mechanism to permit the carriage to be shifted and restored to its initial position for starting another line by exerting pressure against the free end of the 35 lever in the direction in which it is desired to move the carriage.

It has heretofore been proposed to provide means for spacing and shifting the carriage to initial or starting position by 40 means of a foot lever and intermediate connections between the same and the movable carriage without requiring the removal of the hands of the operator from the keyboard, but such means have proven more or 45 less unsatisfactory in practical use; and the primary object of my invention is to provide a simple, efficient and inexpensive carriage shifting and line spacing mechanism, together with a treadle or equivalent means 50 to be actuated by the foot of the operator, so that when the treadle is depressed the carriage will be automatically restored to initial position and at the same time the paper roller will be turned sufficiently to 55 space for the next line; the connections be-

tween the carriage and treadle being such that a very slight movement of the treadle will effect the desired movement of the carriage.

Another object is to provide a foot-lever 60 and coöperating means for accelerating the movement of the platen or paper roll when desired to insert the paper, as at the beginning of an operation, or for the purpose of removing the paper at the completion of 65 a line, or at the end of a page, instead of turning the platen by hand as in machines as heretofore constructed.

The invention will first be hereinafter more particularly described, with reference 70 to the accompanying drawings, which are to be taken as a part of this specification, and then pointed out in the claims at the end of the description.

In said drawings, illustrating a preferred 75 form of embodiment of my invention, Figure 1 is a diagrammatic plan view of a typewriter with my improvements applied thereto, showing the carriage in the position it occupies at the end of a line; Fig. 2 is a rear 80 elevation of the same; Fig. 3 is a detail perspective view of the line spacing mechanism, showing the actuating lever and connections in position for effecting the return movement of the carriage by continued pressure 85 upon the foot lever or treadle after the paper roll has been turned the space of a line; also showing in separated relation certain parts used for adjusting the line spacing device to cause the paper roll to space 90 one, two or more lines, as desired; Fig. 4 is a detail transverse section on a slightly enlarged scale taken on the line 4—4 of Fig. 1, showing the means for imparting a quick 95 movement to the platen or paper roll for inserting or removing the paper at the beginning of an operation or at the completion of a line; Fig. 5 is a detail sectional view of the take-up drums arranged between the 100 foot lever and the line spacing and platen accelerating devices; Fig. 6 is a side view of one of the drums shown in Fig. 5, portions thereof being broken away; Fig. 7 is a diagrammatic side elevation of the typewriter 105 equipped with my improvements, showing the connections with an operating and controlling foot-lever or treadle; Fig. 8 is a bottom plan view of the forward end of the treadle; Fig. 9 is a detail sectional view, on an enlarged scale, of the forward end of the 110

treadle, showing the selective device for throwing into action the devices for imparting a quick movement to the platen or paper roll; Fig. 10 is a diagrammatic plan view 5 of a portion of a typewriter with my improved line-spacing and platen accelerating devices applied thereto, illustrating a modification of the actuating levers shown in Fig. 1; and Fig. 11 is a perspective view of 10 the actuating levers shown in Fig. 10 mounted on a detached portion of the machine frame.

In the accompanying drawings, in which my improvement is shown applied to a type- 15 writing machine of the well-known Remington type and in which the same reference letters are used to denote corresponding parts in different views, the letter A may denote the frame of the typewriter, which 20 may be of the form shown or other construction such as ordinarily used in typewriting machines, according to the type of machine to which the improvement is applied; said frame having mounted thereon 25 the usual carriage carrying a paper roll or platen and movable back and forth across the machine frame in the usual manner of operating typewriters as ordinarily constructed. In Fig. 1 the carriage is shown at 30 the limit of its forward movement, in position for the line-spacing and carriage return mechanism to be actuated for spacing a line and returning the carriage to its initial or starting position.

The letter B denotes the paper roll or platen, to the shaft B¹ of which, at one end, 35 is secured the usual spacing ratchet wheel C, and its actuating lever C¹, carrying a pawl c, which is held normally out of engagement 40 with the teeth of the ratchet by a pin c¹ engaging a cam-faced lug c², on the backward movement of the lever, and dropping into a notch at the rear of said lug. But upon the forward movement of the lever the 45 pawl will engage a tooth of the ratchet and turn the platen sufficiently to space a line or lines, as desired, according to previous adjustment of the line spacing devices, which are shown in operative relation in Fig. 1 50 and in separated relation in Fig. 3. The said line spacing devices include an adjustable stop lever C², mounted loosely upon the shaft B¹ beside the lever C¹ and held in a fixed position upon the shaft by means of 55 a spring pressed dog or catch c³ engaging one of a series of notches in a segmental plate C³, which is also loosely mounted upon the shaft of the paper roll and adapted to be secured in a fixed position by means of a 60 set screw or bolt passing through an arc shaped slot c⁴ in the segment and into a fixed portion of the carriage frame, whereby the several parts of the line spacing device are assembled with provision for adjustment 65 so as to adapt them to turn the roll

the space of one or two or three lines, as desired, according to the notch in the segment which is engaged by the spring catch; the first notch in the series being designed to space for one line only, the intermediate notch for two lines, and the rearmost notch for three lines.

As will be seen, having properly adjusted the lever C², rearward movement of the lever C¹ will cause the pin c¹ to ride up the incline or cam face c² on the lever C² and lift the pawl c out of contact with the teeth of the ratchet, and upon further rearward movement of the lever C¹ the pin c¹ will fall into the notch in the rear of the lug c² and prevent further backward movement of the lever C¹, and the pawl c being held out of engagement with the ratchet will permit free manual rotation of the platen roll in either direction, as usual in the operation of typewriting machines.

As indicated in Fig. 3, the lever C¹ has been thrown forward sufficiently to turn the platen the space of a line, such movement being accomplished by means of a bell-crank lever D, pivotally supported on a standard D¹ mounted upon the carriage, and having one arm connected with the free end of the lever C¹ by a link d, while the other arm thereof is connected by a flexible band, cord or tape 1 to a drum E loosely mounted upon a shaft F which is supported in depending portions of the machine frame, as shown in Fig. 5 of the drawings. Upon the outer side of the drum E and preferably integral therewith concentric with its axis ratchet teeth e are provided for engagement with the pawl e¹ which is pivotally supported upon the inner wall of a smaller drum E¹ loosely mounted upon the hub portion of a stop G, 105 which is adjustably secured on the shaft F by a set screw g so as to adapt said stop to be rotatively adjusted and secured in a fixed position at any desired point upon said shaft. The purpose of the stop G is to limit the rotary movement of the drum E¹ and also to provide a trip for the pawl e¹, and to this end the pawl e¹ has a lug e² projecting therefrom at an angle thereto to adapt it to be brought into contact with the stop G and 110 lifted or thrown out of engagement with the ratchet teeth e, as shown in Fig. 6, and the pawl being thus held clear of the ratchet teeth the drum E is free to rotate in the direction taken by the carriage on its forward 115 movement unaffected by the drum E¹. To rotate the drum E¹ and through it the drum E, a flexible band, cord or tape 1¹, having one end fastened to the drum E¹, extends downwardly and has its other end secured 120 to a foot-lever or treadle, to be presently described, through which movement is imparted to the line spacing and carriage return devices and to the platen accelerating devices, as hereinafter described.

The rotation of the platen or paper roll for spacing purposes is limited by a stop d^1 (Figs. 1 and 3) which is adjustably secured upon the standard D^1 , which supports the lever D , so that the throw of the lever may be varied to correspond with the adjustment of the line spacing devices when set for shifting the platen the space of one, two or three lines. As will be seen, a pull upon the cord or tape 1^a will rotate the drum E^1 in the direction indicated by the arrow in Fig. 6, thereby releasing the pawl e^1 , which will be thrown, by pressure of the spring e^3 , into engagement with a tooth of the ratchet e , thereby rotating the drum E and drawing out the tape $1, 1^a$, causing the lever D to rock upon its pivot and move the spacing lever sufficiently to rotate the platen the space of a line or lines, and at the end of such spacing movement the lever D will contact with the stop d^1 , whereupon, the lever being held stationary by the stop, continued pull upon the tape will move the carriage across the machine frame and restore it to its initial or starting position, at which point the tension or pull upon the tape being removed, the actuating levers will be returned to their original or normal position by the action of a spring upon the usual hand-operated spacing and carriage returning lever X (Fig. 1) and intermediate connections with the lever C^1 including the connecting rod x , such as employed in type-writing machines in common use, so that further description of said hand-operated lever and its connections with the lever C^1 is deemed unnecessary. The spring controlling the lever X has sufficient power to overcome any counter-acting force of the spiral spring within the drum E , the function of which is merely to take up slack in the tape or cord 1 or to keep the same taut. The cord or tape 1 is secured at one end to the outer periphery of the drum E , or a laterally projecting peripheral flange thereon, and to the inner side of said flange is secured one end of a spiral spring E^2 , the other end of which is secured to the stationary shaft F on which the drum is loosely mounted, so that the tension of the spring is exerted in taking up any slack in the tape 1 . By depressing the foot lever or treadle downward pull is exerted upon the tape 1^a , releasing the pawl e^1 from engagement with the stop G , whereupon the pawl will be forced into engagement with a tooth of the ratchet e by pressure of a spring e^3 thereon and as the drum E^1 rotates it will impart rotary movement to the drum E in the same direction. The rotation of the drum E^1 is opposed by a spiral spring E^3 having one end secured to the inner wall of the drum E^1 , and the other end secured to the hub portion of the adjustable stop G , as shown in Fig. 6. When the tension or pull upon

the tape 1^a is released it will be returned to normal position by the spring E^3 and in this position the pawl e^1 will be thrown out of engagement with the ratchet e , by contact of the lug e^2 with the stop G , allowing free rotation of the drum E as the carriage travels across the machine drawing out the tape 1 .

For the purpose of actuating the line spacing and carriage return devices and also the platen accelerating devices by foot instead of by the hand of the operator, I provide a foot lever or treadle I , which is pivoted intermediate its ends on a support I^1 arranged upon the floor in such position that the operator may conveniently depress the longer arm thereof with his foot and thereby exert a downward pull upon the tape which connects the free end of the lever with the drum E^1 . But I will first describe what I term the platen accelerating device, which is shown combined with the mechanism for actuating the line spacing and carriage return devices, but which is capable of use independently thereof, if desired, as will hereinafter more clearly appear. To this end I place upon the shaft B^1 of the paper roll a spur pinion K (Fig. 4) which meshes with a large spur gear K^1 , loosely mounted upon the hub screw k which carries the ratchet actuating lever L , which in turn carries a pawl k^1 pivoted thereto and adapted to engage the teeth of the larger gear K^1 , when the lever L is thrown forward and impart rotary movement thereto and through it rapidly rotate the pinion K , thereby imparting a quick rotary movement to the platen or paper roll of sufficient duration to remove the paper at the end of a letter or line, or for the purpose of inserting a sheet of paper at the beginning of an operation. The lever L is connected by a link m with one arm of a bell-crank lever M , which is pivotally mounted on the machine frame and to the other arm of which is secured one end of a flexible band, cord or tape 2 , the other end of which is secured to a drum H which is mounted beside the drum E , preferably on the same shaft, and is actuated by a pawl and ratchet connection with a smaller drum H^1 in the same manner that the drums E and E^1 are actuated; said drum H being connected with the actuating lever I by means of a cord or tape 2^a and connections as hereinafter described. On the carriage frame is secured a segmental rack N , beside which is placed a stop-lever O which has a rearwardly projecting finger terminating in a laterally projecting lug o arranged in the path of movement of the lever L so as to serve as a stop to limit the rearward movement of the lever L by contact with said lug.

As the gear K^1 is much larger than the pinion K with which it meshes its rotation

will impart a quick movement to the paper roll due to the difference in the diameters of the two gears. As in the case of the line spacing devices, when the lever M contacts 5 with the stop m^1 , it will be held stationary against said stop and the pull on the tape 2 will be transmitted to the carriage, thus returning it to normal or initial starting position in a manner similar to that already 10 described with reference to the operation of the line spacing and carriage return devices actuated by the tape 1 and its connections with the foot lever or treadle I. The pull upon the lever M through the medium of 15 the foot-lever and intermediate connections is opposed by the action of a spring P, which, upon the release of the tension or pull upon the tape 2, will return the lever M to its initial position, thus restoring the 20 actuating lever L to its initial or starting position as determined by the position of the stop o on the stop lever O with which it contacts.

Depending from and pivotally connected 25 to the lower ends of the tapes 1^a and 2^a, respectively are rods 1^b and 2^b which are slidably fitted within sleeves 1^c and 2^c, rising from and each having a swiveled connection at its lower end with the treadle I, 30 to adapt it to serve as a guide for the rod and to tilt slightly when the foot lever is depressed, so as to insure free sliding movement of the rods within the sleeves; there being sufficient clearance between the rods 35 and the inner walls of the sleeves to prevent frictional contact and impede or prevent free movement of the rods. These rods are heavy enough to exert a slight pull on the tapes 1^a and 2^a just sufficient to keep them 40 taut without turning the drums.

On the under side of the treadle I is a keeper plate Q having depending apertured lugs q to receive and guide a sliding locking plate R; said plates also having apertures therein through which the rods 1^b and 2^b pass. On the under side of the lever I, and connecting it with a pendant arm of 45 a trip lever T, is secured a coiled or other suitable spring S which is also connected 50 by a link t with the locking dog R so as to cause the latter to normally grip the rod 1^b, in order that when the treadle is depressed while the trip lever T is undisturbed it will exert a pull upon the tape 1^a 55 only for actuating the line spacing and carriage return mechanisms; the tape 2^a meanwhile being unaffected, by reason of the fact that the rod 2^b slides freely through the tube 2^c and the apertures in the keeper 60 plate and sliding dog; but when the trip lever T is depressed by the foot of the operator, the sliding dog R will move forward, disengaging the rod 1^b and engaging the rod 2^b, and the foot lever being also 65 depressed, a pull will be exerted upon the

tape 2^a and through it upon the drums H and H¹, and the tape 2 and its connections with the platen accelerating devices, thereby imparting a quick rotary movement to the platen, and as the pull upon the tape 70 2 is continued, (the arm of the lever M to which the tape 2 is attached having been brought into contact with the stop m^1) the carriage will be drawn back to its initial or starting position. During this operation the grip of the dog R upon the rod 1^b is released so that it may slide freely through the guide sleeve and treadle, thus permitting a downward pressure upon the treadle for the purpose of operating the 75 platen accelerator without affecting the line spacing devices. When the pull upon the tape 2 is released the spring P will return the parts to normal position. At the same time, pressure upon the trip lever T 80 being released, the spring S will draw the sliding dog R back, disengaging the rod 2^b and engaging the rod 1^b, so that the line spacing devices may be operated independently of or without affecting the platen 85 accelerator. I thus provide simple and efficient means whereby the operator may select whichever mechanism he may desire to operate, for the purpose of actuating the platen, to impart a quick movement there- 90 to, for the purposes stated, or the line spacing devices, either of which may be operated at will without interfering with the operation of the other, thus leaving it to the choice of the operator to impart an 95 accelerated movement to the platen, for the purpose of inserting the paper on the paper roll at the beginning of an operation, or for removing the paper therefrom at the end of an operation, and the platen ac- 100celerating devices being thrown out of action, the line spacing devices will be brought into position for action without affecting the platen accelerator until it is desired to again operate the platen to 105 quickly remove the paper or insert a new sheet.

In Figs. 10 and 11 of the drawings I have illustrated a modification in which a plurality of bell-crank levers are used instead 110 of single bell-crank levers connecting the tapes with the line spacing and platen accelerating devices as shown in Fig. 1, a bell-crank lever D^x being interposed in the connections between the lever D and link 115 d, corresponding with the lever D and link d, connecting with the tape 1, in Fig. 1, and a lever M^x being interposed in the connections between the lever M and link m, corresponding with the lever M and link 120 m connecting with the tape 2 in Fig. 1.

It will be understood of course that various changes may be made in the details of construction and arrangement of parts without departing from the spirit and scope 130

of my invention; hence I do not desire to be limited to the specific construction and arrangement illustrated and described. It should also be understood that the word "tape" as used in the appended claims may include either a chain, cord or other suitable flexible connection between the drums and the line spacing and platen accelerating devices and between said drums and the foot lever or treadle.

Having thus described my invention, what I claim as new and desire to secure by Letters Patent is:

1. The combination in a typewriter, of line spacing and carriage return devices and means for actuating the same by the foot of the operator, comprising a treadle, and flexible connections between said treadle and said devices, including a differential drum interposed in said connections and a spring for each drum element tending to turn it in a direction opposed to the action of the other spring, one spring adapted for taking up slack and holding said connections taut.

2. The combination in a typewriter, of line spacing and carriage return devices and means for actuating the same, comprising a treadle and intermediate flexible connections including a differential drum over which said connections pass, the larger and smaller drum elements being independently rotatable in opposite directions, and each having a spring acting thereon to turn it in a direction opposed to the action of the other spring, and means on one drum engaging means on the other for causing the two drums to rotate together in one direction only.

3. The combination in a typewriter, of line spacing and carriage return devices and means for actuating the same, comprising a treadle and intermediate flexible connections including a differential drum over which said connections pass, the larger and smaller drum elements being independently rotatable in opposite directions, each drum element having a spring acting thereon to turn it in a direction opposed to the action of the other spring, and means on one drum engaging means on the other for causing the two drums to rotate together in one direction only.

4. The combination in a typewriter, of line spacing and carriage return devices and means for actuating the same, comprising a foot lever, flexible connections between said lever and said devices, a differential drum over which said connections pass, the larger and smaller drum elements being independently rotatable in opposite directions upon the same axis, and means on one drum engaging means on the other for causing the two drums to rotate together in one direction only, together with a spring acting on each drum element to turn it in a direction

opposed to the action of the other spring; one spring tending to rotate the larger drum and hold said connections taut.

5. The combination in a typewriter, of line spacing and carriage return devices and means for actuating the same, comprising a foot lever, flexible connections between said lever and said devices, a differential drum over which said connections pass, the larger and smaller drum elements being independently rotatable in opposite directions upon the same axis, and means on one drum engaging means on the other for causing the two drums to rotate together in one direction only, together with a spring acting on each drum element to turn it in a direction opposed to the action of the other spring; one spring tending to rotate the larger drum and hold said connections taut, and means carried by the smaller drum for engaging and imparting movement to the larger drum in one direction only, together with means for releasing the engagement between the two drums and rotating the smaller drum to restore it to initial starting position.

6. In a typewriter, line spacing devices, and devices for imparting a rapid rotary movement to the paper roll, in combination with a treadle, flexible connections between said line spacing devices and treadle, and between said paper roll accelerating devices and treadle, and means on said treadle whereby the operator may effect the desired line spacing or impart an accelerated movement to the platen by foot-pressure on said treadle.

7. In a typewriter, the combination with line spacing devices, means for actuating said devices by the foot of the operator, comprising a treadle, flexible connections between said treadle and line spacing devices including a bell crank lever, a link connecting one arm of said bell crank lever with a ratchet actuating lever, a tape connecting the other arm of said bell-crank lever with a drum loosely mounted on a shaft fixed in the machine frame, a spring having one end secured to said drum and the other end to said shaft and tending to hold said tape taut, a smaller drum loosely mounted on said shaft beside the larger drum and a tape connecting said smaller drum with said treadle; said smaller drum carrying a pawl adapted to engage a ratchet wheel on the larger drum, thereby causing the two drums to rotate in unison when the treadle is depressed, and a spring for restoring said smaller drum to initial position after actuating the larger drum.

8. In a typewriter, the combination with line spacing devices, means for actuating said devices by the foot of the operator, comprising a treadle, flexible connections between said treadle and line spacing devices including a bell crank lever, a link connect-

- ing one arm of said bell crank lever with a ratchet actuating lever, a tape connecting the other arm of said bell-crank lever with a drum loosely mounted on a shaft fixed in 5 the machine frame, a spring having one end secured to said drum and the other end to said shaft and tending to hold said tape taut, a smaller drum loosely mounted on said shaft beside the larger drum and a tape 10 connecting said smaller drum with said treadle; said smaller drum carrying a pawl adapted to engage a ratchet wheel on the larger drum, thereby causing the two drums to rotate in unison when the treadle is depressed, and a spring for restoring said smaller drum to initial position after actuating the larger drum, together with means for limiting the movement of said smaller 15 drum in a backward direction and disconnecting it with the larger drum.
9. In a typewriter, the combination with line spacing devices, means for actuating said devices by the foot of the operator comprising a treadle, flexible connections 20 between said devices and said treadle including a bell crank lever, a link connecting one arm of said lever with a ratchet-actuating lever, a tape connecting the other arm of said lever with a drum loosely mounted on 25 a shaft fixed in the machine frame, a spring tending to rotate said drum and tighten said tape, a smaller drum loosely mounted on said shaft beside the larger drum and carrying a pawl adapted to engage a ratchet 30 wheel on the larger drum, whereby the two drums are caused to rotate in unison in one direction only, a spring tending to restore said smaller drum to normal position, and a stop for disengaging the pawl from the 35 ratchet on the larger drum and limiting the movement of said smaller drum in a backward direction.
10. In a typewriter machine, line spacing and carriage return devices comprising a 40 ratchet wheel on the shaft of the paper roll, a ratchet-actuating lever carrying a pawl engaging said ratchet, a bell crank lever pivoted on the machine frame, a link connecting one arm of said lever with the 45 ratchet-actuating lever, a stop limiting the throw of said bell crank lever so as to cause the carriage to move with the lever when the latter has rotated the platen the space of a line or lines, a foot lever, and flexible con-
- nnections between said foot lever and said bell crank lever comprising a tape connecting said bell crank lever with a drum loosely mounted on a shaft fixed in the machine frame, a second tape connecting said foot lever with a smaller drum rotatably mounted on said shaft beside said larger drum, together with a spring tending to rotate the larger drum in a direction to keep the tape taut, and a second spring tending to rotate the smaller drum in an opposite direction to the force of the spring acting on the larger drum; said smaller drum carrying a pawl adapted to engage a ratchet wheel on the larger drum when the treadle is depressed and thereby impart rotary movement to the larger drum, thus actuating the line spacing and carriage return devices. 55
11. In a typewriter, the combination with line spacing devices carried by the carriage, a foot-lever and intermediate connections 60 for actuating said devices, mechanism on said carriage for imparting an accelerated movement to the platen or paper roll, and means on said foot lever whereby the operator may actuate either the line spacing devices or the platen accelerating mechanism at will; the line spacing devices being unaffected by actuating the platen accelerating mechanism, and vice versa. 65
12. In combination with the line spacing devices of a typewriter and devices for imparting an accelerated movement to the platen, a treadle and intermediate connections for actuating said line spacing devices and said platen accelerating devices; said connections including two tapes leading over drums to said treadle and devices carried by the treadle normally in working connection with one tape for actuating one set of said devices and adapted to effect a working connection with the other tape for actuating the other set of said devices and simultaneously throw out of action the set of devices which are normally in working connection. 70
13. In testimony that I claim the foregoing as my own, I affix my signature in presence of two witnesses. 75
